[57] CLAIM

The ornamental design for a luminaire housing, as shown and described.

DESCRIPTION

FIG. 1 is a perspective view of a luminaire housing showing my new design.

FIG. 2 is a side elevational view of the luminaire housing of FIG. 1.

FIG. 3 is a perspective view of a second embodiment of my design.

FIG. 4 is a side elevational view of the luminaire housing of FIG. 3.

FIG. 5 is a perspective view of a third embodiment of my new design.

FIG. 6 is a side elevational view of the luminaire housing of FIG. 5.

FIG. 7 is a sectional view taken generally along line 7—7 in FIG. 2.

FIG. 8 is a sectional view taken generally along line 8—8 in FIG. 4.

FIG. 9 is a sectional view taken generally along line 9—9 in FIG. 6.
